TENSIOMETER FOR YARN CONING
MACHINESHerbert Naumann, Elizabethton, Tenn., assignor
to North American Rayon Corporation, New
York, N. Y., a corporation of Delaware

Application August 7, 1941, Serial No. 405,825

5 Claims. (Cl. 73—144)

1

The present invention relates to the winding of thread and more particularly to a tensiometer for apparatus for winding rayon thread into cones or similar packages of predetermined hardness.

Most of the artificial silk yarn now produced is wound in the form of cones which at the present time are considered the most suitable form of package for use by textile converters. A particular demand that is made by these converters is that these cones must possess a definite hardness, since not only the build-up of the cone but also the satisfactory unwinding of the thread are dependent upon the proper degree of hardness of the cone. This hardness is generally determined by a conventional hardness tester, such as a "Durometer." Thus, in order to furnish the converters with cones of the proper build-up and hardness it is necessary for the thread manufacturers to maintain a constant check on the degree of hardness of the wound cones. Any off-standard cones must be rewound until, upon measurement, they are found to be of the prescribed hardness. When it is borne in mind that a coning machine usually winds simultaneously some 6 cones and that the simultaneous winding of that number of cones consumes approximately from 2½ to 16 hours, depending upon the winding speed, the denier of the yarn and the size of the cone, it will be realized that the waste of time in producing even a few off-standard cones, i. e., cones of unsatisfactory hardness and build-up, is a factor which considerably affects the economical production of rayon cones. Heretofore, the number of off-standard cones has been of such a magnitude that the necessity of re-winding off-standard cones has introduced an expensive time factor in the rayon industry. In addition, any change in the type of yarn or in the preparation or sizing agent used for the yarn was heretofore accompanied by the production of a large number of off-standard cones which had to be rewound before being acceptable to the converters.

When the problem was first approached by those skilled in the art, it was realized that thread tension must be the controlling factor in determining cone hardness, it being obvious that tightly wound convolutions of thread will produce a harder package than loosely wound convolutions. Furthermore, in most of the conventional winding equipment now in use by rayon manufacturers, it is possible to adjust the tensioning of the thread on each unit. Thus, since tension will control hardness and since tension adjustments are possible, it was originally thought

2

that the problem would not be difficult of solution. This, however, did not prove to be the case. Since the means for adjusting tension on a coning machine of conventional design is intended primarily to control tension only to an extent sufficient to insure that the wound package will retain the shape built up by the traverse mechanism, it was found that even if every thread tension adjusting unit on a coning machine is equally adjusted, cones of thread of uniform denier simultaneously wound will vary greatly in hardness although all of them will be sufficiently tightly wound to maintain their shape. Experiments have shown that with a uniform initial setting of the tensioning device on all winding units there may be as much as fifty to one hundred percent variation in tension. This variation seems to be due to the fact that the modulation from maximum to minimum drag on the thread during the winding period occurs in an unpredictable manner despite the fact that it is brought about, in conventional machinery, by increases in the diameter of the wound cone. Thus, conventional adjustment of the conventional machinery is inadequate to control the hardness of wound cones.

Applicant has found that by measuring the tension of a running thread on each winding unit at the beginning and particularly at the end of the winding operation and then measuring the hardness of the cones produced, it is possible to so correlate winding tensions and cone hardness as to permit adjustment of the various units of a winding machine so that all of them will, upon adjustment, produce cones of a uniform predetermined hardness. Conventional tensiometers were found to be impracticable as vibrations and movement of the thread during winding on the unit of a coning machine were so great as to seriously interfere with securing the tension measurements desired. According to the present invention, a plurality of sample cones are wound and the beginning and end tensions of each are recorded. The cones are then examined for their build-up and hardness characteristics and a cone having the desired build-up and hardness is selected. By referring to the recorded tension of the selected cone the tensions of every unit of a coning machine may be quickly and accurately adjusted in such a way as to insure the simultaneous production of a large number of cones which possess the same degree of hardness as the cone from which the beginning and end winding tensions were determined.

55 It is, therefore, an object of this invention to

provide for the winding of thread into cones of a predetermined hardness and uniformity to avoid rejections from customers and the necessity for rewinding with its attendant injury to thread and waste of time of coning machine operators.

It is a further object of this invention to provide an apparatus for the accurate measurement of the tension of thread during linear movement thereof.

By the practice of the teachings of the present invention, it is contemplated that cones of any selected hardness may be produced substantially without the necessity for readjustments of the individual winding units once they have been adjusted for the winding of a certain type and denier of yarn.

Other objects and advantages of this invention will be apparent from the following detailed description of a preferred form of the component process and apparatus in conjunction with the annexed drawings wherein:

Figure 1 is a perspective view of a tension measuring device constructed according to this invention illustrating the operative association thereof with a cone winding machine in tension measuring position;

Figure 2 is a view in plane of the tension measuring device shown in Figure 1, illustrating the manner of connecting the same to the slab catcher rod and knife of a coning machine;

Figure 3 is a view in section taken along the line 3—3 of Figure 2;

Figure 4 is a view in section taken along the line 4—4 of Figure 2;

Figure 5 is a view in section taken along the line 5—5 of Figure 2;

Figure 6 is a view partially in section and partially in elevation taken along the line 6—6 of Figure 2;

Figure 7 is a longitudinal sectional view of the entire tension measuring device illustrating the position of the moving parts thereof during a thread tension measurement;

Figure 8 is a view of a calibrated scale used in registering relative thread tensions;

Figure 9 is a view of another calibrated scale for use in conjunction with the scale of Figure 8; and

Figure 10 is a front view of a winding unit of a conventional coning machine.

Before describing the various steps by the practice of which it is possible to secure wound cones of any selected hardness according to the scale of a Durometer, the new apparatus for determining the tension of thread during linear travel will be discussed.

When thread is wound on a coning machine of conventional construction, it is customary to drive a collecting cone and to draw thread upwardly from a supply package onto such cone. Intermediate the collecting cone and the supply package it is the usual practice to provide some device for the purpose of imparting drag to the thread so as to permit controlling the winding tension. This device is generally known in the industry as "wash board tensioning device." It is this device and the associated members that are shown in Figure 1. It will be seen that as thread is drawn in the direction of the arrow from a supply package not shown to a driven cone 12c, it will pass through pigtail guides 10 and 11, through wash board tensioner 12, between a slab catcher rod 13 and slab knife 14, across stop motion wire 15 and finally through a pigtail guide 16. Since the winding cone is

located above tensioner 12, it is evident that the extent of drag imparted to the thread by tensioner 12 and the winding speed of the cone will determine the tension of the thread passing therebetween and hence the winding tension. According to conventional construction, it is customary for the drag imparted to the thread by tensioner 12 to be controlled by a weight 12a. The position and hence the effect of this weight is controlled by radial movement of the traverse arm 12b caused by the increase in diameter of the wound cone as the winding operation progresses. The reason for this arrangement is that take-up speed increases as the diameter of the winding cone increases. Thus, without adjustment, thread tension would continuously increase from the beginning of the winding operation to the end of the winding operation. To compensate for this, the radial movement of the traverse shifts the weight associated with the tensioner in such a way that drag is progressively decreased as take-up speed increases. On most coning machines it is possible for the operator to control the position of the weight at either the beginning or end of a winding operation, the shifting thereof being automatically effected by suitable linkage in association with the traverse mechanism.

In winding cones of predetermined hardness, it is essential that the winding tension at various stages be known, for it has been discovered, as a part of this invention, that the tension of the thread at some stages in the winding bears an important relationship to the characteristics of the wound cone and that if the winding tensions are controlled in those stages, it is possible to control with accuracy the build-up as well as the hardness of the cone which will be produced. However, before any degree of control is possible, it is necessary to be able to determine accurately the winding tensions at the critical stage in the winding operation. To this end, this invention includes the provision of apparatus for measuring thread tensions between the tensioning device 12 and the winding cone of any winding unit on a winding machine.

The tension measuring device includes an arm 17, mounted for arcuate movement of a predetermined finite amplitude about shaft 18, from a position parallel to the normal path of thread passing from stop motion wire 15 to guide 16, to a thread displacing position, see Figure 3. A spring 19 is employed in driving arm 17 to thread displacing position, while a sleeve 20 is manually rotated to load the spring to the extent necessary to effect the desired angular movement of the arm 17 against the resultant force tending to restore the thread to its normal path of travel. Clearly, since the thread is being pulled by cone 12c from tensioner 12, it will normally follow a straight line path from stop motion wire 15 to guide 16. When the thread is displaced from this path, a force, resolved from the pull of the cone 12c against tensioner 12, tends to restore the thread to its normal path. It is evident that this force is a function of thread tension. Thread tension therefore, is measured through measurement of the compression of spring 19 necessary to displace arm 17 for a finite number of degrees against the resultant force acting through the thread.

Upon reference to Figure 2, it will be noted that shaft 18 is adapted for detachable insertion into the hollow end of slab catcher rod 13. As a consequence, arm 17, which is mounted for arcuate movement about that shaft, will move about

an axis common to the sub catcher bar and so will contact the thread at the same point in its path of travel on any winding unit, the sub bar, the stop motion wire and the pigtail guide bearing a fixed relative position on any unit of any winding machine or, at least, being adjustable to such fixed relative position.

The sub knife 14 also bears a fixed relative position with respect to stop motion wire 15 and guide 16. As sub catcher rod 13 is used to position the device as a whole, knife 14 is used in positioning the path of movement of arm 17. To this end, a disc 21 is mounted on shaft 18 and this disc is provided with a bifurcated member 22 which extends therefrom parallel to shaft 18 (see Figures 2 and 3). Member 22 is adapted for detachable connection to sub knife 14 at the same time that shaft 18 is connected to constitute an extension of sub catcher rod 13. Disc 21 is provided with an arcuate slot 23 through which arm 17 passes and a marker 24. Since sub catcher rod 13 and sub knife 14 always bear a fixed relative position on any coning machine, it will be seen that when shaft 18 engages sub catcher rod 13 and member 22 is brought into registry with knife 14, slot 23 and arm 17 will be automatically positioned with respect to the path of travel of the thread. Similarly, marker 24 will be caused to assume a fixed position with respect to the normal path of the thread between stop motion wire 15 and pigtail guide 16.

Upon reference to Figures 3 and 7, it will be seen that arm 17, after passing through slot 23 in disc 21, passes through a groove 25 in the integral flange 26 of a sleeve 27 which is mounted for rotation on shaft 18. After passing through groove 25, arm 17 is bent down to lie parallel to flange 26. An eye 28 is formed in arm 17 at the end thereof remote from the thread contacting end and a screw 29 passes through this eye into a threaded aperture in flange 26 to fasten the two securely together. A pointer 30 is also attached to flange 26 and extends radially therefrom in spaced relation to thread contacting arm 17. A screw 31 serves to attach pointer 30 to flange 26. The weight of arm 17, pointer 30 and their attaching means is balanced by counter-weight 32 which may be integral with or attached to flange 26. To insure substantially frictionless arcuate movement of the balanced weight of flange 26 and the elements carried thereby, a bearing assembly 33 is interposed between sleeve 27 and shaft 18. A cage 34 is in contact with sleeve 27 while needle rollers 35 actually contact shaft 18. An axial thrust bearing is interposed between bearing assembly 33 and the hub of disc 21. This bearing consists of two annular running surfaces 36 with an interposed annular member 37 carrying ball bearings 38. It is evident that by the use of these bearings and by perfect balancing the weight of the flange, any force necessary to move arm 17 against the thread will be substantially equal to the resultant force tending to return the thread to its normal path, friction being so reduced as to avoid interference with the accuracy of the determinations.

To effect movement of arm 17, the operator manually grips sleeve 20 at a knurled portion 39 and turns the same in a clockwise direction as viewed in Figure 1. Sleeve 20 is connected to a sleeve 40 which is mounted for rotation on shaft 18 while the outer surface of sleeve 40 constitutes a shaft around which sleeve 20 turns. Sleeves 20 and 40 are keyed together by a set screw 41. Sleeve 40, on the other hand, is attached by ax-

ially extending keys 42 to still another sleeve 43. Helical spring 19 extends between this sleeve and flange 26, the free ends thereof being attached as shown in Figure 7 by passage through suitable drilled apertures. A press ring 44 serves to maintain axially extending keys 42 in position.

It will be noted that sleeve 20 bears a calibrated scale 24a which underlies the path of arcuate movement of pointer 30. Thus, when sleeve 20 is rotated to compress spring 19, it will cause sleeve 27, its integral flange 26, the pointer 30 and arm 17 carried thereby, to move in the same direction. In effecting a tension measurement, sleeve 20 is rotated sufficiently to move pointer 30 from the Figure 3 position to a position in registry with marker 24. Since pointer 30 and arm 17 are both permanently fastened to flange 26 a fixed distance apart, arm 17 will displace the thread from its normal path a distance equal to the distance of angular movement of pointer 30. Because of the provision of marker 24, the operator always knows how far to move pointer 30, and hence arm 17. Thus, the displacement angle of the thread is always a constant, since it will be recalled that the position of marker 24 is predetermined by the connection between member 22 and sub bar 14. This being the case, thread tension is the only variable. While the angular movement of pointer 30 and arm 17 is always the same for each tension measurement made, sleeve 20 will have a varying amplitude of movement for it always moves at least as far as pointer 30 and additionally sufficient to load spring 19 enough to drive arm 17 through its complete path of movement against the tension of the thread. Thus, the greater the tension of the thread, the greater the amplitude of movement on the part of sleeve 20 to bring about the fixed angular displacement of pointer 30 and arm 17.

Scale 24a, which is illustrated in Figure 8, may be conveniently calibrated to read in grams tension. As shown, the scale would therefore read up to fifty-five grams beyond which point the reading would be fifty-five grams plus the additional reading brought up by the completion of the full turn of sleeve 20. To avoid confusion and to render scale 24a always easy to read, adjustment of the initial loading of spring 19, prior to any movement of sleeve 20, is provided. Also, a stop pin 45 is associated with sleeve 20 and with disc 21, the two pins cooperating to prevent the turning of sleeve 20 more than one complete revolution.

It will be noted that sleeve 20 is provided with a number of spaced apertures 46 extending parallel to shaft 18 and arranged for cooperation with the shank of screw 41 (see in particular Figure 5). Furthermore, there are three threaded apertures 47 in sleeve 40 each adapted to receive screw 41. Apertures 47 are spaced apart for a different distance than apertures 46 so that in almost any conceivable relative position of sleeves 20 and 40, one of the apertures 47 will be in registry with one of the apertures 46.

If screw 41 is withdrawn from one of the apertures 47 far enough so that its shank no longer projects into one of the apertures 46, sleeves 20 and 40 may be relatively rotated. The effect of this relative rotation is to increase or decrease the loading of spring 19. Thus, if spring 19 is to be loaded, the operator withdraws screw 41 and grips the knurled portion 39 of sleeve 20. While sleeve 20 is firmly held against movement, a knurled portion 48 of sleeve 40 is gripped and

that sleeve is rotated in a clockwise direction. When sleeve 40 is rotated, sleeve 43 will be driven through keys 42 and it will be recalled that one end of spring 19 is attached to sleeve 43. In order that the extent of pre-loading of spring 19 may be discerned without measurement, a marker 49 is arranged on sleeve 40 in position to register with a calibrated scale 50 on sleeve 20. Scale 50 permits adjustment of the instrument in fractions of grams. Thus a pre-loading of spring 19 is possible, which pre-loading will be readable on scale 50. Of course, if it were possible to fabricate spring 19 so that it would have the same torsional strength at a given torsion angle, pre-loading would not be necessary. However, in order to provide scale 24a with a uniform graduation the initial tension of spring 19 is made individually adjustable. The limit of preloading should not be more than plus or minus two hole spacings as shown in Figure 5. Otherwise the spring would not be suitable for this instrument since it would lack sufficient sensitiveness for low range load measurements. The pre-loading of spring 19, once accomplished, is maintained by locking sleeves 20 and 40 together by the insertion of screw 41 in any two of apertures 46-47 at a point where the tension of spring 19 is adjusted to the graduation of scale 24a.

It is evident that in the device as thus far described, the arm 17 (Fig. 3) will tend at all times to move in a counterclockwise direction. This tendency arises because of the loading of spring 19. In order to maintain arm 17 in starting position, that is, at the left extremity of slot 23, as viewed in Figure 3, a spring 51 is employed. This spring extends between sleeve 40 and a sleeve 52 which is keyed by a set screw 53 to shaft 18. The action of spring 51 is in a counterclockwise direction and its force is sufficient to maintain arm 17 in the starting or left-hand position, regardless of the loading of spring 19, until such time as knurled portion 39 of sleeve 20 is gripped and that sleeve is turned in a clockwise direction to move arm 17 for a fixed distance into thread displacing position due to the loading of spring 19.

A cylindrical housing 54 surrounds sleeve 52 and spring 51, this housing having an end plug 55 which fits over shaft 18 and a set screw 56 which locks the same in fixed position with respect to the shaft. Upon reference to Figure 7, it will be seen that set screw 56 locks cylinder 54 and plug 55 against relative movement and against movement with respect to shaft 18. Housing 54 acts as a handle which the operator may grip during such times as shaft 18 and bifurcated member 22 are being placed in position on slab catcher bar 13 and slab knife 14, respectively.

When the device described above is used for measuring the tension of thread passing between two fixed points such as stop motion wire 15 and pigtail guide 16, shown in Figure 1, the operator grips the handle 54 and inserts the free end of shaft 18 into the hollow of slab catcher rod 13 and simultaneously moves the bifurcated member 22 into cooperating engagement with slab knife 14. Arm 17 will be disposed in a plane parallel to the plane of the thread in its normal path of travel. When a measurement is to be taken, the operator turns sleeve 20 by the use of thumb and forefinger as shown in Figure 1. The sleeve is turned in a clockwise direction until pointer 30 moves into registry with indicating marker 24 at the top of disc 21. It has been

previously stated that pointer 30 and arm 17 are attached to flange 26 of sleeve 21 in fixed spaced relation. Thus, when pointer 30 has moved into registry with marker 24, arm 17 will have been moved for exactly the same distance. This distance is predetermined and is used in controlling the calculations by which the gradations on calibrated scale 24a are made up. The advantage of accurate control of the extent of movement of arm 17 will be recognized when it is borne in mind that the force necessary to displace thread to any extent from its normal path of travel, although always a function of thread tension, will bear a different relation to thread tension at any extent of displacement. Thus, if arm 17 were not moved for a fixed distance, it would be necessary upon taking each tension determination to measure the extent of thread displacement as well as the force necessary to effect that displacement and to compute thread tension from the two variables. Accordingly, disc 21 with its associated member 22 form an important function in definitely locating the radius of slab bar 13 in which marker 24 will lie, since this marker serves to indicate the extent of movement of arm 17 thereby reducing thread tension determinations to a force measuring problem involving but a single variable, it being apparent that the thread always bears a fixed position with respect to the slab bar. By the time that pointer 30 is in registry with marker 24, arm 17 will have moved through slot 23 from left to right as viewed in Figure 3. The movement of sleeve 20, however, will be considerably greater than the movement of arm 17 since sleeve 20 must be moved sufficiently to load spring 19 to that extent required in overcoming the resultant force tending to restore the thread to its normal path of travel between stop motion wire 15 and pigtail guide 16. This lost motion will be measured by the difference in relative position of the scale 24a and pointer 30. Thus, pointer 30 and zero on scale 24a are in registry in Figure 3. However, in Figure 2, which represents a tension measurement, the reading will be above zero an extent dependent upon the resistance offered by the thread to displacement by the arm 17. It will be realized that sleeve 20 moves with, as well as with respect to pointer 30. Thus, if a hypothetical case were assumed in which the thread offered no resistance whatsoever, sleeve 20 and pointer 30 would move together until pointer 30 was in registry with marker 24. The reading on scale 24a, however, would be zero.

As has been pointed out above, there seems to be no correlation between the initial winding tension of thread being wound into cone form and the extent of hardness of the cone produced. This is true despite the fact that practically all coning machines are provided with means for modulating the drag imparted to the thread by the tensioning board with increases in cone diameter. Apparently, the difficulty arises from the fact that the rates of change of drag with respect to increases in cone diameter are not constant on all winding units of a coning machine even when the starting drags are equal. The inaccuracy may be due to slight variations in the physical characteristics of threads of like material and equal denier, as well as variations in the effect of the mechanical parts controlling the wash board tensioning mechanism, etc.

It has been discovered, however, as a part of this invention that there is a correlation between the beginning and end tensions in cone

winding and the hardness and build-up of the finished cone. If a number of winding units, adjusted to an equal modulation rate, are started with identical tension adjustments, the end tensions of these units will vary, and as a result of these variations the hardness of cones wound on these units will vary proportionately. If, on the other hand, the tensioning units of a number of coning machines are adjusted to a predetermined beginning thread tension and the end point toward which modulation of tension will move is controlled, the cones produced on these coning machines will be of equal hardness. "Modulation" as used in this specification is intended to indicate the rate of drag reduction of tensioner 12 in response to increase in effective diameter of cone 12c, see Figure 10.

In accordance with the present invention, the beginning and end winding tensions are determined as follows. Yarn of uniform type and denier is simultaneously wound into cones of the desired size on several winding units subsequent to the adjustment of the tensioning devices on these units to a setting which from practical experience is known to yield cones of approximately the desired degree of hardness. After the cones have been completely wound to the desired size, they are removed from the winding spindles and subjected to a hardness test by means of a "Durometer" or any other standard hardness testing device. This preliminary coning experiment generally yields at least one cone which possesses the desired hardness. This cone is singled out in order to be used as a master cone for the production of duplicate cones, i. e., cones having the same degree of hardness and uniformity in build-up as the master cone. For the determination of the end winding tension, the aforementioned master cone, still fully wound, is placed back into winding position on the winding unit on which it was prepared and immediately upon commencement of the winding operation a measurement of the thread tension is taken with the apparatus which is a part of the present invention. This measurement gives the end winding tension of the thread. The master cone is then removed from the winding spindle and an empty cone core having the same dimensions as the core used in winding the master cone is placed into winding position thereon. Thread of the same type and denier as that of the master cone is wound onto the core and concurrently the tension of the running thread is measured by means of the aforesaid instrument. The tension determined by this measurement represents the beginning winding tension of the master cone.

The beginning and end winding tensions thus determined are now used as a basis for the tension adjustment of all of the winding units on which the master cone is to be duplicated. Each one of these winding units is first adjusted to the predetermined end winding tension by means of temporarily placing the aforementioned master cone on the winding spindle and concurrently measuring the thread tension. Since the master cone is fully wound at the time the tension measurement is made, the drag adjusting means 12a are disposed in their end or minimum drag position. After the measurement, these are adjusted while the winding on of thread is continued until an end tension corresponding to that which produced the desired result in the master cone is attained. Thereafter, the master cone is exchanged for an empty core and the winding unit is adjusted to the predetermined beginning

tension if such an adjustment should be found necessary, whereupon the winding of the cone is continued until it has reached the same diameter as the master cone of the desired hardness. It will be found that all of the cones produced on the winding units so adjusted will possess the same hardness and build-up as the master cone. Once the winding units have been adjusted in the manner hereinbefore described, no additional tension adjustments are necessary provided the type and denier of yarn, the size of the cone, the winding speed, etc., remain constant. In order to expedite the adjustment of a large number of winding units, the use of a plurality of dummy cones in place of a master cone is suggested. These dummy cones are of a size substantially equal to the size of the master cone which is to be duplicated on a large scale. When dummy cones are used, the procedure for adjusting the winding units will be identical with that one described with respect to the master cone. It has been found that adjustments of the beginning tensions are rarely necessary, and in those instances where they are required they are so slight that no material change in the end tension takes place for which the winding unit has previously been adjusted. Modulation of thread tension with cone diameter will occur in the normal way but when the traverse mechanism reaches the point that it assumed on the dummy cone at the time the end tension adjustment was made, the tension will be that one necessary for producing a cone of desired hardness.

In winding cones according to the foregoing process, it has been found that identical beginning and end tensions on all winding units will produce cones of uniform hardness. Generally speaking, however, all other factors remaining constant, increases in denier of thread will result in decreases in cone hardness. Thus, to insure cones of any predetermined hardness denier variations must be considered. The following table will serve as an example of the particular beginning and end tensions necessary to produce cones of predetermined hardness from threads of various deniers, all unmentioned factors being constant:

Denier	Beginning Tension	End Tension
75/30		
75/60	20	5
100/40		
100/60	24	6
100/100		
125/42	25	
125/52		7
150/42		
150/60	27	8
150/100		
50/15	17	
50/24		4

The cones listed above were wound at an average room temperature of 82° F. and an average relative humidity of 56%. The largest outside diameter of these cones after complete winding was approximately 5 1/4", and all of the cones mentioned in the foregoing table possessed a hardness of sixty according to measurement by a Durometer. Any changes in the aforementioned factors would necessitate different beginning and end tensions as those given in the above table in order to produce cones of a hardness of sixty as measured by a Durometer.

It is to be understood that the form of my invention, herewith shown and described, is to be

11

taken as a preferred example of the same, and that various changes and variations may be made without departing from the spirit of my invention or the scope of the subjoined claims.

I claim:

1. A device for measuring the tension of thread during linear travel between two fixed stationary points on a winding machine comprising, a thread contacting arm, means for detachably supporting the arm for arcuate movement about an axis fixed with respect to one of the fixed points to displace the running thread from its normal path of travel between the points, a manually operable driving member, a resilient torque transmission connecting said arm and said driving member, registering members movable with said arm and said driving member for indicating in terms of thread tension the energy absorbed by said transmission in moving said arm against the resultant force tending to restore the thread to its normal path of travel.

2. A device for measuring the tension of thread during linear travel between two fixed stationary points on a winding machine comprising, a thread contacting arm, means for detachably supporting the arm for arcuate movement in a limited path about an axis fixed with respect to one of the fixed points to displace the running thread to a limited extent from its normal path of travel between the points, a manually operable driving member, a spring for transmitting torque connecting said arm and said driving member, registering members movable with said arm and said driving member for indicating in terms of thread tension the energy absorbed by said spring in moving said arm for the full amplitude of its fixed path against the resultant force tending to restore the thread to its normal path of travel.

3. A device for measuring the tension of thread during winding on a coning machine provided with a slab bar and a guide in fixed spaced relation thereto comprising, a thread contacting arm adapted to act on thread at a point between the slab bar and the guide, means adapted for detachable connection to the slab bar for supporting said arm for movement in an arcuate path to displace thread laterally, means for predetermineding the position of said path in relation to normal path of travel of the thread, means normally maintaining said arm in parallel relationship with respect to the normal path of travel of the thread from the slab bar to the guide, including resilient means for driving said arm away from normal position to displace thread laterally, and means for loading said resilient means to the extent necessary to move the arm for the full length of its path of travel, and means for registering the extent of loading of the resilient means in terms of thread tension.

4. The combination with a winding machine having a plurality of thread winding stations each including a thread guide and a thread tension regulating device in spaced relation, the thread

12

tension regulating device of each thread winding station having a slab bar and a slab knife, of a thread tension measuring device adapted to be interchangeably associated with the thread winding stations, said thread tension measuring device having thread tension detecting means adapted to contact a thread running between the thread guide and the thread tension regulating means of a thread winding station and means carried by the thread tension measuring device adapted to so detachably connect the thread tension measuring device to the slab bar and slab knife of the thread tension regulating device of a thread winding station that the thread tension detecting means contacts the running thread at a predetermined distance from the thread tension regulating device irrespective of the thread winding station with which the thread tension measuring device is associated.

5. The combination with a winding machine including a multiplicity of identical winding units each of which includes a fixed thread guide and a slab catcher in fixed spaced relation to the fixed thread guide, said slab catcher having a slab bar and a slab knife cooperating herewith, of a thread tension measuring device adapted to be interchangeably associated with the individual winding units, said thread tension measuring device comprising a displaceable thread engaging arm adapted to engage a thread travelling between the slab catcher and the fixed thread guide, means cooperating with the thread engaging arm for registering in terms of thread tension the amount of energy required to overcome displacement of the travelling thread by the thread engaging arm and means carried by the tension measuring device for detachably engaging both the slab bar and slab knife for accurate location of the point of contact of the thread engaging arm with the travelling thread irrespective of the thread winding unit with which the thread tension measuring device is associated.

HERBERT NAUMANN.
